Fig. 1.

Fig. 2

Fig. 3.

FIG. 1 is a front elevation of a ladder;

FIG. 2 is an enlarged side view of a rung and a portion of an upright of the ladder as shown in FIG. 1;

FIG. 3 is an enlarged sectional view taken along lines III—III of FIG. 1.

The characteristic feature of my design resides in the specific appearance and configuration of the end of the rungs as shown in FIG. 2.

I claim:

The ornamental design for a ladder with non-slip rungs, substantially as shown and described.
